UNITED STATES PATENT OFFICE

161,532

WINDOW FOR TELEVISION VIEWING SCREENS

Carl Reynolds, Jr., Birmingham, Mich., assignor
to Aveo Manufacturing Corporation, Cincinnati,
Ohio, a corporation of Delaware

Application July 1, 1950, Serial No. 10,930

Term of patent 14 years

(Cl. D56—4)

To all whom it may concern:

Be it known that I, Carl Reynolds, Jr., a citizen of the United States, residing at Birmingham, in the county of Oakland and State of Michigan, have invented a new, original, and ornamental Design for a Window for Television Viewing Screens, of which the following is a specification, reference being had to the accompanying drawings, forming a part thereof.

In the drawings:

Fig. 1 is a front view of a window for television viewing screens, showing my new design; and

Figs. 2 and 3 are sectional views taken along the lines 2—2 and 3—3, respectively, of Fig. 1, in each case looking in the direction of the arrows.

I claim:
The ornamental design for a window for television viewing screens, as shown.
